HOT-WATER HEATER.

1,243,604.

Specification of Letters Patent.

Patented Nov. 13, 1917.

Application filed May 6, 1915. Serial No. 36,957.

To all whom it may concern:

Be it known that we, GEORGE C. GILL, GEORGE S. SINCLAIR, and PATRICK J. MOAKLER, citizens of the United States of America, residing in the city of Holyoke, county of Hampden, and State of Massachusetts, have invented certain new and useful Improvements in Hot-Water Heaters, of which the following is a specification.

10 This invention relates to improvements in hot water heaters of the type in which a series of coiled pipes or heating units are enclosed in a suitable casing. The coils are heated by means of a suitable burner which is located at the lower ends of the coils and near the lower portion of the casing, whereby the heated products of combustion will come into contact with the coils as they pass upward through the casing in the well known manner. These coils are connected and arranged for permitting the water to simultaneously flow through all of them from the bottom toward the top, the opposite ends of the coils being in communication with suitable manifolds or heads with which the supply and discharge ends are directly connected. Heretofore, in water heaters of this type it has been the common practice to arrange the heating coils in vertical planes in parallel relation to each other, or, in horizontal planes one above the other. One of the objects of the present invention is to provide a hot-water heater in which the internal space or volume of the inclosing casing is substantially filled with the heating coils, said coils being so nested or twisted one with relation to the other that they act as a baffle plate to prevent the heated products of combustion from the burner from flowing freely through the casing, and thereby utilizing a high percentage of the heat units contained in the fuel when the same is burned, whether it is oil, gas, or alcohol. Broadly considered, our invention comprises a plurality of spirally arranged nested water heating coils or units that are connected at their opposite ends to a common manifold having suitable means for attaching thereto supply and discharge pipes for the cold and hot water, said coils being located within a suitable inclosing casing at the lower end of which is located a suitable heater.

Referring to the drawings:

Figure 1 is a vertical sectional view of the casing taken in a plane through the axis thereof and showing in full lines the inclosed coils which are arranged in spiral nested relation to each other;

Fig. 2 is a horizontal plan view on the line 2-2 of Fig. 1, looking in the direction of the arrows and showing the manner in which the coils are arranged and slightly nested together in contacting relation;

Fig. 3 is a horizontal sectional plan view of one of the manifold elements taken in a plane through the axis of the reservoir.

Fig. 4 is a view showing a modified form of heater in which the outlet manifold is at the top of the casing.

Referring to the drawings in detail: 1 designates a suitable inclosing casing, having its lower end formed with a flange portion 2 and its upper end having attached thereto a cap 3 to which pipe connection 75 may be made for carrying away the products of combustion, it being understood that the pipe is connected to the flange portion 4. This cap is secured to the member 1 by means of the bolts shown at 5'. Formed in the side of the casing 1 are openings 5 and 6. Passing through these openings is the externally threaded end of the water receiving and discharge manifolds 7 and 8, a sectional detail of the lower one of which is shown in Fig. 3. The outer end of each of the manifolds is formed with a flange 9 and the cylindrical part adjacent the flange is threaded to receive a securing and attaching nut 10. Each of the manifolds 7 and 8 shown in Fig. 1 is formed with bosses or projections 11 having an opening therethrough which communicates with the interior of the manifolds. These projections 11 are for the purpose of receiving and securing the ends of the spirally arranged heating coils or units 12, which are located within the casing 1. These projections, as will be observed, are arranged on the opposite sides of the manifolds in staggered relation to each other whereby, when the opposite ends of the coils are attached to the projections on one side of one manifold and to the projections on the opposite sides of the other manifold they will assume positions that are spiral to the axis of the cas-

ing. In other words, the spiral arrangement is the same as rotating the manifolds through 180° . As shown the heater is provided with four of these heating coils or units which are attached at their upper and lower ends to the manifolds 7 and 8, respectively. It is to be understood that we do not limit ourselves to any specific number of heating coils or unit. It should be particularly observed that these coils or heating units are not located in vertical parallel planes but that each of them is twisted more or less so as to stand in a spiral relation to the vertical axis of the casing, that is to say, the opposite ends of the heating coils or units are twisted or rotated through any suitable arc, in the form shown they are twisted or turned through an arc of 180° . The twisting arrangement is effected by any suitable means whereby the coils are partially nested or interlocked with relation to each other, as clearly shown in Figs. 1 and 4.

The distance apart of the projections 11 and the diameter of the coils which are attached to these projections is such that when the manifolds 7 and 8 are turned relative to each other in horizontal or parallel planes, the coils 12 will be twisted about the axis of the casing, causing the turns of the coils to slightly nest one within the other, as shown. This nesting of the coils or heating units serves or acts as a baffle plate to the free upward flow of the heated gases or products of combustion from the burner 13 in their passage through the casing 1 and the outlet cap 3. By reason of this nesting or spiral arrangement of the heating coils with relation to each other which causes them to act as a baffle plate, a very high degree of heating efficiency is obtained by reason of the fact that more of the heat units contained in the fuel is imparted to the water contained in the coils. This twisting of the coils with relation to the vertical axis serves to place them very much closer together and thus a greater amount of heating surface is obtained in a given space than is the case where the coils are not nested. The lower manifold 7 is formed with a centrally located projection 14 for attaching an inlet pipe thereto. This projection is provided with a suitable plug 15 for closing the same when it is not in use. The centrally located pipe connection is to be used only when it is inconvenient to make the usual pipe connections at the side of the casing, as indicated in Figs. 1 and 4, as occasions very often arise where the construction of the building or the location of the inlet cannot be conveniently attached at the side of the heater; a central connection can then often be conveniently made by means of the threaded projections 14 which are normally closed by the plug 15. A suitable drip plate is shown at 16 that is located

below the burner, in order to collect any water of condensation that may drip from the coils 12 when the burner is first lighted.

It may be mentioned that the gas inlet pipe 17 is not located exactly in the axial line of the casing but at one side so that should it be desired to connect an inlet pipe to the projection 14 it would have room to pass down through the burner 13 in the axial line of the casing.

By twisting or winding the heating coils closely together in a rope-like manner for the purpose of making them serve as a baffle plate the heated gases are brought directly into contact with the coils. It will be observed that in twisting the coiled pipes or units about each other and in spiral relationship to the axis of the casing the inner sides of the coils or turns of each coiled pipe are brought into direct engagement with each other in the same manner as the inner sides of the strands of a rope and close to the axis of the casing. The center portion of the coiled pipes therefore, practically closes the space about the axis of the casing and results in obtaining a mass of heating coils that are arranged closely together and which effectively serve as a baffle to the free upward flow of the heated products of combustion and thereby greatly increasing the efficiency of the heater. These twisted coiled pipes, it will be observed, substantially fill the interior space of the inclosing casing from the central axial line to the inner surface of the inclosing casing. If a baffle plate is used the heated gases are partially cut off from contact with the coils, whereas, in the present invention the coils themselves act as a baffle device. Fig. 2 clearly shows the heating coils in contact with each other in a partial nested relation, while the spiral arrangement is clearly shown in Fig. 1.

In the preferred form of heater shown in Fig. 4 the manifolds 7' and 8' are attached to the casing 1 and cap 3 in the same manner as already described in connection with Fig. 1. In this form of heater the lower manifold 7' is not provided with a central projection for an inlet pipe connection as shown in Fig. 1. The upper manifold 8' is formed with an upward extension 14' for connecting an outlet pipe thereto. This extension, as shown is located at one side of the center and parallel with the axis of the casing and is secured to the cap 3 by means of the nut 10. This arrangement is more convenient for attaching the outlet hot water pipe than that shown in Fig. 1. This upper manifold is not provided with a centrally located projection like that shown in Fig. 1, or, in other words the arrangement of inlet and outlet pipe connections is the same as those usually employed in making the necessary pipe connections to

the usual kitchen or other hot water supply tank. The same arrangement of heating coils is employed in the construction shown in Fig. 4 as already referred to in connection with the arrangement shown in Fig. 1.

What we claim is:

1. A hot-water heater comprising heating coils located within a suitable inclosing casing, a heater at the lower end thereof, manifolds having their inlet and outlet ends terminating in and secured to the casing, one end of each coil is connected on one side of one manifold and its other end is connected on the opposite side of the other manifold, whereby said coils are arranged in spiral relation to the axis of the casing and the inner surfaces of the turns of the coils are twisted against each other in rope-like fashion to substantially fill the inclosing casing and to serve the purpose of a baffle to the free upward flow of the heated products of combustion from the burner through the casing.

2. A hot water heater comprising heating coils located within a suitable inclosing casing, upper and lower manifolds extending across the interior of the casing and having one end attached to the casing, the upper and lower ends of the heating coils being mutually connected to the upper and lower manifolds, the outlet end of the upper manifold being located at one side of the center line of the casing, the manifolds having projections located on their opposite sides and to which projections one end of each coil is connected on one side of one manifold and its other end is connected on the opposite side of the other manifold, whereby said coils are twisted or arranged in a spiral relation to the axis of the casing, the turns of the coils on their inner sides being in contact with each other in rope-like fashion, and a suitable heater for heating the coils.

3. A water heater comprising a plurality of coiled pipes which are arranged within a suitable inclosing casing, a burner at the lower end of the casing, upper and lower manifolds directly attached to the casing and to which the ends of the coiled pipes are mutually connected and which serve as a common connection with water receiving and discharge pipes, said pipes being arranged in the casing in such a relation to the axis of the casing that the inner surfaces of the relationship of the coiled pipes being such that the inner sides of said pipes engage each other in rope-like manner and substantially fill the interior of the casing from the axis of the casing outward to the inner surface of the casing, whereby said coils will serve as a baffle to the free upward flow of the hot gases from the burner.

4. A water heater comprising an inclosing casing, a plurality of coiled pipes located therein, a suitable burner at the lower

end of the casing, tubular manifolds located at the top and bottom of the casing in horizontal planes and extending across the interior of the casing, said manifolds having hollow projections on the opposite sides of the same, the projections having the ends of the coils secured thereto, said coils being arranged in a spiral manner about the axis of the casing with the inner sides of the coils engaging each other in rope-like fashion to serve as a baffle to the free upward flow of the heated gases from the burner.

5. A water heater comprising, in combination, an inclosing casing, a plurality of coils located therein, a suitable burner at the lower end of the casing, tubular manifolds secured to the casing near the upper and lower ends, the manifolds extending substantially across the interior of the casing and having hollow projections on the opposite sides of the manifold, said projections being arranged in a staggered or alternate manner with relation to each other on opposite sides of the manifolds and with their axes lying in a horizontal plane, the coils having one end attached to one of the manifolds on one side and the other end of the coils attached to the other manifold on the opposite side of the same in order to cause the coils to assume positions that are spiral or twisted with relation to the axis of the casing.

6. A hot water heater, comprising in combination with an inclosing casing and a burner at its lower end, of a plurality of coiled pipes within said casing, upper and lower water receiving and discharge manifolds secured to the casing, said manifolds being formed with spaced hollow projections in zig-zag arrangement on their opposite sides to which the ends of the coiled pipes are attached, said coiled pipes being arranged in spiral relation to the vertical axis of the casing in rope-like manner and having the turns of the coiled pipes at their inner sides engaging the turns of the adjacent coiled pipes so as to form a mass of coiled pipes or coils which practically fill the interior space of the inclosing casing, whereby said twisted or spirally arranged coiled pipes will serve as a baffle to the free upward flow of the heated products of combustion from the burner.

7. A water heater comprising in combination with an inclosing casing, a burner, a plurality of coiled pipes in the casing, supply and discharge manifolds to which the ends of said pipes are mutually connected, said pipes being twisted together into connecting relation in a rope-like manner about the axis of the casing, the innermost points of the turns of each coiled pipe being close to the axis of said casing and the diameter of the twisted coils being substantially equal to the internal diameter of the casing, where-

4
by the twisted coils will serve to retard the free upward movement of the heated gases through the casing.

8. A hot water heater comprising in combination with an inclosing casing, a burner at the lower end of the casing, a plurality of coiled water heating pipes located in the inclosing casing, a transversely arranged manifold located at the upper and lower ends, respectively, of the said casing and to which they are attached, the manifolds having spaced hollow projections on the opposite sides of the same for attaching the ends of the coiled water heating pipes to the manifolds, each coiled water heating pipe having one end attached to a projection on one side of a manifold and its other end attached to a projection on the oppositely considered side of the other manifold for the purpose of arranging said pipes in a spiral relation to the axis of the inclosing casing and for causing the turns of said pipes to engage in a rope-like manner to cause said

pipes to serve as a baffle to the free upward flow of the heated products of combustion from the burner, all constructed and arranged for the purpose herein set forth.

9. A hot-water heater comprising in combination with an inclosing casing, of a plurality of coiled water heating pipes twisted about each other in rope-like manner with the inside portions of the turns of said pipes being in contacting relation but leaving an open centrally located space between the turns of said coils, inlet and outlet manifolds to which the ends of the said coils are connected, a burner at the lower end of the casing, said twisted arrangement of the heating pipes resulting in substantially filling the inclosing casing to serve as a baffle to the free upward flow of the heated products of combustion.
